UNITED STATES PATENT OFFICE.

CLIFTON O. GAMMELL, OF GREEN BAY, WISCONSIN, ASSIGNOR OF ONE-HALF TO A. L. NELSON, OF GREEN BAY, WISCONSIN.

PAPER-CONVERTING MACHINE.

Application filed January 14, 1925. Serial No. 2,394.

This invention relates to paper converting machines and, in its more specific aspect, involves mechanism for folding a paper sheet suitably for a napkin.

5 The primary object of the invention is the provision of a machine comprising cooperating instrumentalities whereby sheet material from a parent roll, in its passage through the machine, is cut into pieces of 10 uniform size, each piece folded a plurality of times, and finally delivered in the form of a harpoon or dart-folded napkin, as shown and described in applicant's pending application Serial No. 723,413, filed June 30, 1924.

15 A further object of the invention is to provide a device of this character wherein all the cooperating instrumentalities are positively actuated by a single source of power.

20 A still further object of the invention is to provide a sheet folding machine which is durable in construction, composed of comparatively few and simple parts, is continuous and automatic in its operation, and requires practically no attention on the part 25 of the operator other than the providing of a new roll of paper and the removal of the completely folded napkins from the machine.

30 With these and other objects in view, as will become apparent as the description proceeds, the invention consists of the novel features of construction, combinations of elements, and arrangements of parts herein- 35 after to be fully described and pointed out in the claims.

A full and complete understanding of the invention may be obtained from a consideration of the following detailed description 40 taken in connection with the accompanying drawings forming a part of the specification, it being understood that while the drawing shows a practical form of the invention, the latter is not confined to the 45 showing thereof, but may be changed and modified so long as such changes and modifications mark no material departure from the salient features of the invention as hereinafter fully described and claimed.

50 In these drawings:

Figure 1 is a view in plan of a napkin folding machine constructed in accordance with a preferred embodiment of the invention;

Fig. 2 is a view in side elevation thereof; 55
Fig. 3 is a view in horizontal section, on the line 3—3, Fig. 2;

Fig. 4 is a view in front elevation of the device;

Fig. 5 is a vertical section on the line 5—5, 60 Fig. 1;

Fig. 6 is an enlarged detail view illustrating the feed roll drive;

Fig. 7 is a fragmentary view in section taken on the line 7—7, Fig. 1, illustrating 65 the cut-off mechanism;

Fig. 8 is a view in plan of the napkin prior to folding;

Fig. 9 is a view in plan of the sheet after 70 the first fold;

Fig. 10 is a similar view after the second fold;

Fig. 11 is a similar view after the third fold; and

Fig. 12 is a similar view of a completely 75 folded napkin.

In the particular embodiment of the invention illustrated in the accompanying drawings, the reference numeral 1 designates, generally, a substantially rectangular metallic frame of the machine to which are secured or upon which are mounted the various elements of the machine. An auxiliary frame 2, including spaced arms 3, serves to support the supply roll 4 of paper or other suitable material in such a position that the sheet may be drawn therefrom by cooperating rolls 5 and 6, these rolls being driven in a manner hereinafter to be described.

The machine, preferably and as shown, includes sheet cutting mechanism, folding mechanism and delivery mechanism.

Cut-off mechanism.—The sheet, after its passage between the rolls 5 and 6, is thereby pushed across a flat table 7, and cut-off mechanism (about to be described) is arranged in line with the roll 4 to cut the sheet into substantially square pieces of uniform size. This mechanism comprises a lower bed knife 8 (Fig. 7) which has one edge serrated and is stationary with respect to the table 7. A vertically movable knife 9 cooperates with the knife 8 to cut the sheet of material. The knife 9 is similarly serrated and the serrations of the two knives register for the cutting operation. The knife 9 is carried by a frame 10 which, in turn, is mounted on one

extremity of an arm 11, the opposite extremity of which is fast on a rock-shaft 12, the latter being journaled in uprights 13 upstanding from the machine-frame 1. Fast 5 on but depending from the rock-shaft is a link 14 connected to one end of an arm 15, the opposite end being mounted at the upper end of a lever 16 fulcrumed intermediate of its ends on a shaft 17 suitably mounted on 10 the machine-frame, the lower extremity of the lever being foot-shaped. The knife 9 is normally held in a raised position by means of a pair of springs 18, each spring having one of its ends secured to the knife 15 and its other end to a three-sided frame 19 upstanding from the machine-frame.

Preferably and as shown, means are provided for holding the sheet momentarily stationary during the cutting operation, and 20 such means include a shoe 20 mounted at the lower end of a spring-actuated presser member 20 carried by the movable knife. The shoe is adapted to engage the sheet and hold it against the stationary knife during 25 the movement of the movable knife and thus insure proper and a clean-cut severing of the sheet.

Preferably and as shown, means are provided for periodically actuating the structure, already described, for operating the movable knife and, incidentally, the sheet-engaging member, such means including a cam carrier 21 and comprising a rotatable cam-shaft 22 on which are mounted a plurality of cams, one of which, 23, is positioned to engage the foot-shaped extremity of the lever 16. Movement of the knife 9 is accomplished when the cam 23 engages the lever 16 to rock the same on its fulcrum and there- 40 by operate the arm 15, the link 14, the rock-shaft 12, the arm 11, and the knife-carrying frame 10. By this action the movable knife is depressed to engage the stationary knife and, incidentally, to cut the sheet. As the 45 knife descends, the presser-member 20 engages the sheet and holds it momentarily and until the movable knife is returned to normal position under the action of the pair of springs.

50 *Folding mechanism.*—Preferably and as shown, the folding mechanism comprises a plurality of pairs of rolls, each pair being carried by aligned shafts suitably journaled in the machine-frame, and each roll being 55 positively driven in a manner to be described. Means are provided which cooperate with each pair of rolls for tucking the sheet of material and starting its passage between the rolls which fold the sheet and carry it 60 forward.

65 *First fold.*—The portion of the sheet when cut off lies across the table 7 and is in proper position, over the pair of cooperating horizontal rolls 24 and 25, to be tucked there- 70

by the first fold tucker 26. It will be observed that the rolls 24 and 25 are disposed at an angle of 45 degrees with respect to the supply roll 4 in order that the sheet may be folded centrally substantially on a line connecting the diagonally opposite corners thereof. Preferably and as shown, the first tucker 26 comprises a transverse tucking-blade 27 carried by the ends of a pair of arms 28, the other ends of the arms being mounted on an oscillatory shaft 29 suitably journaled in the frame 1 in such position that the blade 27 is disposed directly above the meeting line or bite of the two rolls 24 and 25. Preferably and as shown, the means 75 for actuating this mechanism comprises a depending link 30 fast at its upper end to the shaft 29 and pivotally connected to an arm 31 which has pivotal connection at its other end with the upper end of the lever-arm 32. The lever-arm 32 is mounted intermediate its ends on the rock-shaft 17 journaled in the opposite sides of the frame 1. The depending portion of the arm 32 is positioned so as to be engaged by the cam 34 80 which extends radially from the cam-shaft 22 and revolves therewith. Downward movement of the arms 28 and blade 27 is accomplished when the cam 34 by its engagement with the lever-arm 32 rocks the shaft 29 through the connection established by the arm 31 and the link 30. By this action the blade 27 forces the center of the sheet between the rolls 24 and 25 which crease or fold the sheet and carry it downward. The tucker-blade 27 is normally maintained in 85 retracted position, with the arms 28 in engagement with the horizontal portion of an upstanding three-sided frame 35, by means of a coil spring 36 having one of its ends secured to the frame 1 and its other end to the lower end of the link 30. The napkin which, after its passage between the rolls 24 and 25, is in the form shown in Fig. 8, is 90 guided by the spaced vertical plates 37 to a 95 position in which its folded side rests upon the horizontal supporting surface 38 directly before the vertically disposed rolls 39 and 40. The apex of the napkin in this position 100 aligns with the dividing line between the two rolls 39 and 40, and the napkin is in position 105 to be folded a second time.

110 *Second fold.*—Preferably and as shown, the mechanism for producing the second fold in the napkin comprises a transverse tucker-blade 41 carried by the free ends of a pair of spaced swing arms 42 which are pivotally mounted at their outer ends on a vertical shaft 43, the arms being of such 115 length as to position the blade in substantial alinement with the meeting line or bite of the rolls 39 and 40. A spiral spring 44, having one of its ends secured at an intermediate point to one of the arms 42 and its 120 other end fast to a bracket 45, serves to 125

yieldingly maintain the blade 41 in retracted position with the arms 42 engaging the stationary stop frame 46.

Means for periodically moving the blade 5 into position to direct the sheet between the rolls 39 and 40 is provided, and comprises an operating arm 47 having its ends pivotally connected respectively to an intermediate point on one of the arms 42 and to the short arm 48 of the bell-crank-lever 49, which is pivotally mounted on the frame 1, as at 50, in such position that its longer arm 51 will be engaged by a cam 52 carried by the cam-shaft 22 upon each revolution 15 of the latter.

The sheet or partially folded napkin, which now has two folds and is in the form shown in Fig. 10, is fed by the aid of gravity through the chute 52 to a position, with 20 its bottom edge at an angle of 30 degrees from the horizontal, directly before the co-operating rolls 53 and 54, preparatory to the making of the third fold.

Third fold.—Preferably and as shown, 25 the mechanism for making the third fold comprises a tucker-blade 55 mounted upon the ends of a pair of spaced arms 56, the other ends of which are fixed to a vertical shaft 57 having suitable bearing on the machine-frame 1. An arm 58, fast at one end to the shaft 57 and extending radially therefrom in a plane substantially at right angles to the plane of the arms 56, carries adjacent its outer end a depending cam-arm 59 which is adapted to be periodically engaged by a cam 60 mounted on the cam-shaft 22. A spring 61, having one of its ends secured intermediately to one of the arms 56 and its other end secured to a stationary part of the frame, serves to yieldingly hold the tucker-blade 55 in retracted position with the arm 56 in engagement with the stop 62. Upon engagement of the cam 60 which the cam-arm 59, the free end 40 of the arm 58 is forced inwardly, thus rotating the shaft 57, which rotation moves the blade 55 into engagement with the napkin to tuck the latter between the rolls 53 and 54 which fold and feed it onward. The 45 napkin, which is now in the form shown in Fig. 11, passes by gravity down the chute 63 to a position, with its apex down and its sides each forming an angle of 30 degrees to the vertical, directly in front of the rolls 50 64 and 65, preparatory to the making of the fourth and last fold.

Fourth fold.—Preferably and as shown, 55 the instrumentality for making the fourth fold comprises a tucker-blade 66 mounted on the free ends of a pair of spaced swing arms 67 which are pivotally mounted, as at 68, to the machine-frame 1. Means is provided for actuating the free ends of the arms 67 and the blade 66 forwardly to tuck 65 the napkin between the rolls 64 and 65, and

comprises a depending arm 68 fast at its upper end to the machine-frame and pivotally connected at its lower end to a substantially horizontal arm 69, the other end of which is joined at an intermediate point 70 to the upper arm 67. A cam 70 extending radially from the cam-shaft 22 is so positioned and of such a length as to periodically engage the arm 68 and drive its lower end inwardly. By reason of the connecting link 75 or arm 69, the forward end of the swing arms carry the blade 66 into position to tuck the napkin between the rolls which carry it forward. A spring 71, having one of its ends fast at an intermediate point to one of the spring arms 67 and its other end fast to a stationary part of the machine-frame, serves to maintain the blade 66 in retracted position with the said arm in engagement with the stop-plate 72. The napkin, after 80 its passage between the rolls 64 and 65, is deposited by the latter in the horizontal trough 73.

Delivery mechanism.—Preferably and as shown, delivery mechanism, provided to 90 carry the napkins as they fall into the trough 73 outwardly past the guard-hooks 74 to an accessible position, comprises a packer 75 95 slideable in the trough 73 and carried on the end of a driving rod 76. Actuating means to reciprocate the packer in the trough 73 comprises an arm 77 having pivotal connection at one of its ends with the end of the driving rod 76 and being fast at its other end to the vertical shaft 78 which is rotatably mounted as at 79 on the machine-frame 1. An arm 80, having one of its ends fast to the top of the shaft 78, has pivotal connection at its other end in the form of a ball-joint 81, with the free end of the crank 100 arm 82 which is pivoted at its other end to the outer side and adjacent the periphery of the wheel 83 carried on the end of the cam-shaft 22. Upon rotation of the wheel 83, reciprocatory movement is imparted to the crank arm 82 and through the arm 80, shaft 78 and arm 77 to the driving rod 76 which carries the packer 75. The guard-hooks 74 serve to protect the napkins from contact with the folding rolls 64 and 65, as 110 the packer is timed in its movement to engage the napkins as soon as they are deposited into the trough 73.

Driving mechanism.—Preferably, the driving mechanism comprises a belt driven by a 120 suitable source of power, as an electric motor (not shown), which passes over the driving pulley 85 mounted on the end of a shaft 86 suitably journaled in the machine-frame 1 and carrying the roll 24 of the 125 mechanism for making the first fold. The roll 25 is driven by means of cooperating pinions 87 and 88 on the shaft 86 and shaft 89, respectively. On the end of the shaft 86 opposite the pulley 85 is provided a small 130

4
sprocket gear 90 which is operatively connected by means of a chain 91 to a similar although larger sprocket-wheel 92 mounted on a short shaft 93 having suitable bearing 6 in the frame 1. Between the sprocket-wheel 92 and the frame, and also mounted on the stub-shaft 93, is a smaller driving sprocket-wheel 94 which, through the agency of an endless sprocket-chain 95, serves to drive 10 several of the instrumentalities of the machine, as will now be explained.

The chain 95 passes downwardly from the sprocket-wheel 94 around a sprocket-wheel 96 on the end of a short shaft 97 which has 15 suitable bearing on the frame and extends inwardly having on its inner end a beveled gear 98 which, by engagement with a similar gear 99 on the lower end of a shaft 100, serves to drive the roll 39. The roll 40 is 20 driven by means of interengaging gear-wheels 101 and 102 mounted, respectively, on a shaft 100 and a shaft 103 which carries the roll 40. The chain 95 passes from the sprocket-wheel 96 over a similar wheel 104 25 on the end of a shaft 105. This shaft, journaled in suitable bearings on the frame, carries on its other end a beveled gear 106 which, by its engagement with a beveled gear 107 at the lower end of a shaft 108, serves to drive the shaft 108 upon which is 30 mounted the roll 53. The cooperating roll 54 is driven by the engagement of pinions 109 and 110 mounted on the shafts of the respective rolls. The chain 95 passes from 35 the sprocket-gear 104 under a sprocket-gear 111 which is mounted on the end of a shaft 112 which passes through a suitable bearing mounted on the machine-frame 1 and having on its inner end a beveled gear 113 40 which engages a beveled gear 114 to drive a shaft 115 on which the roll 64 is mounted, the roll 65 being driven from the shaft 115 by the interengagement of pinions 116 and 117 on the shafts of the respective rolls. 45

The chain 95 then passes over an idler sprocket-gear 118, which is adjustably mounted on the frame 1 in order to serve as a chain tightener, and upwardly over a large sprocket-wheel 119 which is mounted 50 on the end of the main cam-shaft 20, and thence back over the sprocket-wheel 94. On the short shaft 93, exteriorly of the sprocket-wheel 92, is mounted a beveled gear 120 which meshes with a similar gear 121 on the 55 end of a vertical shaft 122, there being a small beveled gear 123 adjacent the top of the shaft 122 which engages with a large beveled gear 124 mounted on a horizontal shaft 125 which carries the measuring roll 5. 60

Preferably and as shown, the roll 6, which is carried by a shaft 126 journaled in supports 127 upstanding from the machine-frame 1 at opposite sides thereof, is driven solely by the rotation of the roll 5. The latter is pressed downwardly by its own weight 65

and by springs 128 which are positioned in the supports 127 with their opposite ends in engagement with the top plates 129 and the movable journal blocks 130, respectively.

Operation.—In operation, upon actuating 70 of the pulley 85 by a suitable source of power, the rolls of each pair of folding rolls, 24 and 25, 39 and 40, 53 and 54, 64 and 65, and of the feeding rolls 5 and 6 are caused to rotate in opposite directions, and the cam-shaft 22 is revolved at a uniform rate of 75 speed by the driving mechanism hereinbefore described. The cams 23, 34, 52, 60 and 70 extend radially from the shaft 22 at the proper angles to consecutively actuate the 80 cut-off mechanism, the first, second, third, and fourth tucker mechanisms in the order named upon each complete revolution of the shaft 22.

The three-sided bracket 141 upstanding 85 from the auxiliary frame 2 has one end of tension arm 142 adjustably connected thereto, the other end bearing down upon the roll to retard movement thereof.

As the sheet of material is drawn from the 90 supply roll by means of the feeding rolls, a substantially square piece or napkin is severed therefrom by the cut-off mechanism, as it travels across the table into position over the first pair of rolls, to be directed therebetween by the first tucker. The napkin is fed 95 downwardly by the first roll and falls into position before the second set of rolls, to be directed therebetween by the second tucker. Upon leaving these rolls, the napkin is guided 100 downwardly at an angle of 30 degrees to the horizontal, is stopped before the third set of rolls, and is directed between the latter by the third tucker. The napkin then travels by gravity to its position before the 105 last set of rolls and is tucked therebetween by the fourth tucker, whereupon it falls into the delivery trough and is carried away from the last rolls by the delivery mechanism. 110

What I claim is:

1. A web converting machine including a web feeding mechanism, a mechanism for severing the web into sheets, and a plurality of sheet folding mechanisms operative successively upon each cut sheet, said mechanisms being so arranged that the cut sheets fall by gravity from each folding mechanism to the next succeeding mechanism. 115

2. A web converting machine including a web feeding mechanism, a cut-off mechanism operative to cut the web into sheets, a plurality of sheet folding mechanisms so arranged that the cut sheets fall by gravity from each folding mechanism to the next 120 succeeding mechanism, and means for directing the fall of the cut sheets to predetermine the position thereof with respect to a succeeding folding mechanism. 125

3. A napkin folding machine, including, 130

in combination, a cut-off mechanism, a plurality of sheet-folding mechanisms, self-contained means for supplying sheet material to the machine, and means for guiding the severed sheet in a fall by gravity from one folding mechanism to another and, incidentally, to vary its angle in respect to the folding mechanisms for positioning it at different angles preparatory to action by the succeeding folding mechanism.

4. A napkin folding machine, including, in combination, a cut-off mechanism, a plurality of sheet-folding mechanisms operating successively to produce a dart-shaped napkin, self-contained means for supplying sheet material to the machine, and means for guiding the severed sheet in a fall by gravity from one folding mechanism to another and incidentally to vary its angle in respect to the folding mechanisms for positioning it at different angles, preparatory to action by the succeeding folding mechanism.

5. In a web converting machine, a supporting frame including a web supporting table formed with a slot, a pair of coacting folding rolls mounted on the frame beneath said table with their longitudinal axes in alinement with the slot, means for feeding a web of material over the table in a direction acute to the bite of the folding rolls, cut-off mechanism operative to transversely sever the web, and tucker mechanism operative to force the approximate center of the cut sheet through said slot into the bite of the rolls.

6. In a web converting machine, a supporting frame, a pair of coacting horizontally-disposed folding rolls mounted thereon, means for feeding a web of material over said rolls in a direction acute to the bite thereof, cut-off mechanism operative to transversely sever the web, tucker mechanism operative to force the approximate center of the cut sheet into the bite of the rolls, and a plurality of folding mechanisms carried by the frame and successively operative on the cut sheet.

7. In a web converting machine, a supporting frame, a pair of coacting horizontally-disposed folding rolls mounted thereon, means for feeding a web of material over said rolls in a direction acute to the bite thereof, cut-off mechanism operative to transversely sever the web, tucker mechanism operative to force the approximate center of the cut sheet into the bite of the rolls, and a plurality of folding mechanisms carried by the frame and successively operative on the cut sheet, each folding mechanism including a pair of vertically-disposed coacting rolls, a tucker member movable with respect to the bite thereof, and an actuator for the tucker blade.

8. In a web converting machine, a sup-

porting frame, a pair of coacting folding rolls mounted thereon, a table mounted above said rolls and having an elongated slot in alinement with the bite thereof, means for feeding a web across the table in a direction acute to the bite of the rolls, mechanism for transversely severing the web into sheets, and tucker mechanism operative to force the approximate center of the cut sheets through said slot into the bite of the rolls.

9. In a web converting machine, a supporting frame, a pair of coacting horizontally-disposed folding rolls mounted thereon, a table mounted above said rolls and having an elongated slot in alinement with the bite thereof, means for feeding a web across the table in a direction acute to the bite of the rolls, mechanism for transversely severing the web into substantially rectangular sheets, and tucker mechanism operative to force the approximate diagonal center of the cut sheets through said slot into the bite of the rolls.

10. A napkin folding machine comprising a web feeding mechanism, mechanism for cutting the web into sheets, a plurality of sheet folding mechanisms successively operative upon the cut sheets, each of said folding mechanisms including coacting rolls and a folder blade movable with respect to the bite of the rolls, operating means for the web cutting means and for each tucker blade, and cam means for actuating each of said operating means in turn.

11. A machine for converting paper into napkins, including self-contained paper supply means, cut-off mechanism juxtaposed thereto, a series of sheet-folding mechanisms operative successively upon the cut sheets, and means for moving a plurality of sheets through the machine into action thereon by the several folding mechanisms by gravity.

12. A web-converting machine including web-feeding mechanism, severing mechanism for cutting the web into sheets, and a plurality of sheet-folding mechanisms operative successively upon each cut sheet, each folding mechanism effecting the folding of a sheet and also its advance in the machine independent of any other sheet-feeding mechanism.

13. A web-converting machine including web-feeding mechanism, severing mechanism for cutting the web into sheets, and a plurality of sheet-folding mechanisms operative successively upon each cut sheet, each folding mechanism effecting the folding of a sheet and also its advance in the machine independent of the feeding mechanism, the advancing action of each folding mechanism aided by gravity being the sole means for effecting a feeding of the successive sheets through the machine.

14. A web-converting machine including

web-feeding mechanism, severing mechanism for cutting the web into sheets, and a plurality of sheet-folding mechanisms operative successively upon each cut sheet, each folding mechanism effecting the folding of a sheet and also its advance in the machine independent of the feeding mechanism, the several folding mechanisms being disposed relatively to effect further advancing of the cut sheet by gravity alone between each two of the folding mechanisms.

15. A web-converting machine including web-feeding mechanism, severing mechanism for cutting the web into sheets, and a plurality of sheet folding mechanisms operative successively upon each cut sheet, each folding mechanism effecting the folding of a sheet and also its advance in the machine independent of the feeding mechanism, the folding mechanisms being disposed in relatively different horizontal planes to effect further

advancing of the cut sheet by gravity alone between each two folding mechanisms.

16. A web-converting machine including web-feeding mechanism, severing mechanism 25 for cutting the web into sheets, and a plurality of sheet-folding mechanisms operative successively upon each cut sheet, each folding mechanism effecting the folding of a sheet and also its advance in the machine independent 30 of the feeding mechanism, the folding mechanisms being disposed in relatively different horizontal planes to effect further advancing of the cut sheet by gravity alone between each two folding mechanisms, and 35 guiding means associated with the folding mechanisms to predetermine the position of a cut sheet in respect to a succeeding folding mechanism.

In testimony whereof I affix my signature.

CLIFTON O. GAMMELL.
